UNITED STATES PATENT OFFICE

2,485,170

GRAVITY-ACTUATED HIGH-VOLTAGE
SWITCH

Robert P. Roetter, Westmont, N. J., assignor to
Radio Corporation of America, a corporation
of Delaware

Application November 30, 1946, Serial No. 713,195

5 Claims. (Cl. 200—166)

1

This invention relates to electrical switches and has for its principal object to provide an improved gravity-actuated switch, and one particularly characterized by the positive, non-bouncing action of its contacts.

Another and important object of the present invention is to provide a simple, yet rugged, high-voltage switch and one wherein any arc-over which may occur is confined to areas on the switch which are remote from the active surfaces of its contacts, whereby the life of the switch is prolonged by obviating the "pitting" of its said contact surfaces.

Still another object of the present invention is to provide an inexpensive and reliable spring-less switch which shall be suitable for use in a safety system for preventing access to the interior of a high-voltage compartment so long as the power is on.

The invention will be described in connection with the accompanying drawing wherein: Fig. 1 is a partial section, in side-elevation, taken on the line I—I of Fig. 3, of a safety-system incorporating a gravity-actuated switch within the invention, the switch being open; Fig. 2 is a similar view, with the switch contacts closed; Fig. 3 is a front elevational view taken on the line III—III of Fig. 2; and Fig. 4 is a top plan view of the switch.

In the embodiment of the invention which has been selected for illustration, 1 designates the door of a high voltage compartment 2 of a radio transmitter or the like and 3 designates, generally, a gravity-actuated switch constructed in accordance with the principle of the invention and arranged (in a manner later described) to close upon opening the door 1 and to open upon closing of the said door.

The supporting structure for the switch comprises an inverted U-shape frame 4 which is secured, as by screws 5, to the base 2a of the compartment 2, adjacent to the door 1. A bracket 6 comprising two outwardly and downwardly inclined arms 6a, 6b which are secured as by screws 7 to the short (top) arm of the U, serve to support, on their underside, two parallelly arranged, inwardly inclined, downwardly extending porcelain or similar insulators 8, 8a which in turn support a stationary switch-contact 9 having a curved, preferably cylindrical, contact surface 9a. The upper surfaces of the arms 6a and 6b of the bracket 6 carry two upwardly extending flanges 10a and 10b that serve as bearings for the fulcrum or axle 11 of a dependent switch arm 12 which, in the absence of any restraining force, is

2

free to move vertically in the space between the two porcelain insulators 8 and 8a. This movable metal arm 12 comprises a lever of the third class and carries a second or "movable" switch-contact 12a adjacent to its lower or free end for engagement with the stationary contact 8. The switch is thus normally biased by gravity to its closed position (as shown in Fig. 2) but is held open, when the door 1 is closed (as shown in Fig. 1), by the weight of the door 1 (or by the force of its latch, not shown) which is applied to the lever 12 through an adjustable ball-headed stop or arm 13 arranged intermediate the axle or "fulcrum" 11 and the movable contact or "weight" 12a.

It will be observed that the lever arm 12 is grounded both through its axle 11 and, by means of a braided copper strap 14, to the inverted U-shape metal frame 4. Thus, when the door or panel 1 is opened it allows the lever arm 12 to swing down, under the force of gravity, and to engage the stationary contact 8 and thereby to ground the high voltage which is normally supplied to the said contact 8 through an electrical lead 15.

As previously indicated, the principal object of the invention is to provide a switch which shall be characterized by the positive "non-bouncing" action of its contacts. This object is achieved, in accordance with the invention, by so constructing the lever 12 and its movable contact 12a that the force of the lever is largely compressive on the insulators 8, 8a and the movable contact 12a is presented in "wiping" engagement to the stationary contact 9 at an angle of from not less than 5°, nor more than 10°, with respect to a line drawn tangent to the curved contact surface 9a at the point, or line of engagement. As indicated in Fig. 2 of the drawing, the angle of engagement best calculated to prevent bouncing, and arcing due to bouncing, is approximately 6½°.

The movable contact 12a preferably comprises a flat surface, though it may be curved if the curvature is such as to cause it to engage the stationary contact-surface 9a along a line or point, rather than with a seating or nesting type of engagement. When, as in the illustrated embodiment of the invention, the stationary contact comprises a cylindrical surface and the movable contact comprises a flat surface, which is presented at a small angle to the former, the electrical arc normally incident to the grounding of a "live circuit" will jump from the "leading side" (instead of the "bottom") of the cylind-

drical surface 9a to the leading edge 12b of the lever (instead of to the flat surface of the moving contact 12a) and hence will not pit or otherwise mar the active surfaces of either one of the said contacts.

As previously pointed out, when the door 1 is closed it pushes the arm or stop 13 inwardly and hence lifts the lever 12 and breaks the contact between 9a and 12a. This stop 13 is preferably in the form of a screw and is placed near the center of motion, thus, only a small movement of the door 1 is needed to operate the switch and the door cannot be opened far enough to allow some one to insert his hand into the compartment 2 so long as the switch is ungrounded.

It will now be apparent that the present invention provides an improved "non-bouncing" high-voltage switch and capable of operating indefinitely without pitting the active surfaces of its contacts.

What is claimed is:

1. A switch comprising a movable arm having a free-end and a rigid contact adjacent to said free-end, a stationary arm having a rigid contact mounted at a point contiguous the path of movement of said first mentioned contact, at least one of said contacts having a curved surface and being relatively so disposed with respect to the other that upon closing of said switch said path will engage said curved surface at an angle of not less than 5° nor more than 10° with respect to a line drawn tangent to said curved surface at said point.

2. A switch in accordance with claim 1 and wherein said contacts are adapted to engage at an angle of approximately 6½°.

3. A switch comprising in combination; two rigid contacts, one of said contacts having a curved surface and the other of said contacts hav-

ing a substantially flat surface; a gravity biased actuating arm having one of said contacts mounted thereupon so that its path engages the other of said contacts contiguously; said contacts being in such relation that said path meets said curved contact at a small angle with respect to the tangent of said curved contact at the point of contiguity, thus providing a wiping engagement with compressive force between both said contacts, said force being in an outward direction.

4. A combination in accordance with claim 3 with said contact angle being between 5° and 10°.

5. A gravity biased switch comprising a movable arm pivoted about an axis in the form of a lever, an actuating arm between said axis and the free end of said lever, a substantially flat rigid contact adjacent said free end, and a stationary arm having a rigid curved contact surface mounted at a point contiguous the path of movement of said flat contact, said flat contact being disposed on said lever arm so that said path of movement engages said curved contact at an angle of not less than 5° nor more than 10° with respect to a line drawn tangent to said curved surface at said point.
